UNITED STATES PATENT OFFICE.

MARTIN BYE, OF WORCESTER, MASSACHUSETTS, ASSIGNOR TO THE HARRINGTON & RICHARDSON ARMS COMPANY, OF SAME PLACE.

EJECTOR MECHANISM FOR BREAKDOWN FIREARMS.

SPECIFICATION forming part of Letters Patent No. 644,040, dated February 20, 1900.

Application filed December 21, 1899. Serial No. 741,103. (No model.)

To all whom it may concern:

Be it known that I, MARTIN BYE, a citizen of the United States, residing at Worcester, in the county of Worcester and State of Massachusetts, have invented a new and useful Improvement in Ejector Mechanism for Firearms, of which the following, together with the accompanying drawings, is a specification sufficiently, full, clear, and exact to enable persons skilled in the art to which this invention appertains to make and use the same.

The object of my present invention is to provide a simple, efficient, and inexpensive automatic ejector for breakdown shotguns and similar firearms; also, to provide means whereby the ejector mechanism is adapted as a check or stop for limiting the breakdown movement of the barrel.

My invention consists, first, in the peculiarly-constructed latching and releasing devices, combined with the ejector-stem; second, in the peculiar construction of a starting device, in combination with the latching-lever and ejector, and, third, in the provision of a stud in connection with the ejector latching and releasing lever, and a retaining-space in the barrel-hinge lug for the purpose of limiting the movement thereof and checking the tilt of the barrel.

In the drawings, Figure 1 is a vertical section of so much of a firearm as will illustrate the nature of my invention. Fig. 2 is a similar view with the barrel tilted. Fig. 3 is a plan section, and Fig. 4 is a transverse section, at line X X in Fig. 1; and Fig. 5 is a side view of the hinging block or lug and indicating the lever as used without the starter device.

Referring to the parts as shown in the drawings, A indicates the frame, B the barrel, having the lug b thereon and hinged to the fore end of the frame by the hinge-pin a, and C the ejector, consisting of a rod or stem disposed within the usual longitudinal bore C' in the barrel-hinge lug b and having a suitable head c for engaging against the rim of the cartridge-shell in well-known manner, a spring E within the bore at the inner end of the ejector-stem serving for forcing the ejector outward.

The ejector-stem C is provided with a catch-

notch 2 and a stop-shoulder 3 on its lower side, and beneath the said stem I arrange a catch-lever D, disposed within a longitudinal vertical slot in the lug b, which slot coincides with and opens into the bore C'. The catch-lever is pivoted near its rear end on a pin 4, that passes transversely through the parts, so that said catch-lever can swing up and down at its fore end. Its upper surface is fitted with a nose or detent 5 for engaging the notch on the ejector-stem. A suitable spring F is combined with the catch-lever, preferably a coiled wire seated within a recess 6 above the rear end 7 of the lever, as shown, for normally pressing said catch-lever toward the ejector-stem.

Fixed in the lever D at a suitable distance from the fulcrum-pivot 4 I arrange a horizontally-crosswise pin I, the ends of which extend through holes J, formed in the opposite sides of the lug b and project beyond the outer surface thereof for a short distance within recesses 8, formed in the opposite interior cheeks of the frame A. Said recesses are undercut, so as to form horizontal shoulders 10 at the upper part of the inner side surfaces, between which the lug b is embraced, and the wing-studs or ends of the pin I strike against said shoulders when the gun-barrel is tilted, as in Fig. 2. The recesses 8 are best formed by sinking a suitable milling-tool into the top of the frame at 9 and then carrying it horizontally to cut out beneath the shoulders 10 to the required extent.

The diametric size of the openings J is such as to arrest the wing or cross-pin at its top and bottom, thereby confining the movement of the catch-lever within the limit of the ejector-notches, or so that it will swing off from the notch or shoulder 2 only to catch the shoulder 3, and vice versa.

Forward of the catch-lever D, I preferably arrange a starter device K, which consists of a triangular piece of metal mounted within the slot adjacent to the end of the catch-lever and adapted to have a swinging action on the pivot-pin 12. Its top end or point 13 is disposed in a manner to act against the end shoulder of the ejector and its rear or lower part provided with a toe or detent 15, with which the end of the catch-lever engages for

operating the starter when said catch-lever is depressed. The hinge-pin *a* has a handle *16* jointed thereto, as at *17*, which can be folded down into a recess in the side of the frame, *5* as indicated in Fig. 3, or raised for unscrewing the pin.

In operation the act of breaking down the barrel on its hinge brings the ends of the cross-pin *I* against the shoulders *10*, causing *10* depression of the catch-lever *D* and releasing its nose *5* from the notch *2*. At the same time the end of the catch-lever actuates the pivoted starter *K*, causing it to rock backward, swinging its top end against the the ejector-rod *15* and forcing said ejector by a positive movement for starting the shell in the event of its sticking somewhat in the barrel-chamber. The ejector-spring then throws the ejector outward to its full limit of action, which *20* is governed by the shoulder *3* striking the latch *5*. The cross-pin ends by being arranged through the holes *J* bring up against the bottom edge of said holes, and thus, in combination with the shoulders *10*, serve as a check *25* or limiting-stop for the barrels at breakdown position, Fig. 2. When the barrel is brought back to normal position, Fig. 1, the ejector is forced in in the usual manner, and the spring *F* causes the lever *D* to assume its first position *30* in lock with the ejector-notch *2*.

In some instances, if desired, the catch-lever *D* may be employed without the starter *K*, the latter being omitted, as indicated in Fig. 5. Such modification, which I include *35* as a part of my invention, is fully operative for releasing the ejector, but does not apply a positive ejective force at the start, and I therefore prefer the construction as shown in Figs. 1 and 2, in which the starter is employed.

40 What I claim as of my invention, and desire to secure by Letters Patent, is—

1. An ejector mechanism for firearms, comprising the ejector-rod having a notch and stop-shoulder on its under side, an ejecting-spring therefor, a horizontally-pivoted catch-lever within a vertical slot in the barrel-hinging lug, said lever adapted for engaging the ejector-rod notch, a cross-pin fixed in said lever, its ends projecting laterally through *45* openings at the sides of the lug, and a spring for said catch-lever; in combination with the barrel-hinging lug, and the frame provided with interior shoulders or offsets against which the projecting ends of said cross-pin *50* are brought to contact by the breakdown movement of the barrel, substantially as set forth.

2. In a breakdown firearm, the combination, with the ejector-rod having a notch, a *55* stop-shoulder and forward shoulder, and the ejector-spring acting against the same; of the movable catch-lever pivoted within a slot in

the barrel-lug and carrying a nose or detent that engages the ejector-rod, and a laterally-projecting cross-pin that engages offsets in *65* the frame, a spring for said catch-lever, and a pivoted starter-piece mounted within the slot, with its top end engageable with the ejector-rod, said starter operated by movement of the catch-lever, substantially as set *70* forth.

3. In an ejector mechanism for firearms, the combination, of the frame having the opposite inward offsets or shoulders, the barrel-hinging lug having the ejector-bore and slot *75* therein, and the ejector and ejector-spring in said bore, a pivoted catch-lever adapted for locking said ejector, said lever pivoted within the slot of the lug and its moving arm provided with wing-studs or pin ends projecting *80* laterally therefrom and through openings in the sides of the lug for engaging said frame-shoulders, a rearward arm on said lever, a coiled spring supported in a recess above said arm; and an angular starter-block disposed *85* adjacent to the end of said catch-lever, said starter pivoted within the slot, its top angle engageable with the ejector-rod, and its lower rear angle engageable by the fore end of said catch-lever, for operation substantially as set *90* forth.

4. In an ejector mechanism for breakdown firearms, comprising a spring-actuated notched ejector-rod, a spring therefor and a spring-pressed catch-lever fulcrumed in a *95* slot in the barrel-lug; and having the cross-pin fixed therein as a means for operating said catch-lever actuated from the frame by the breakdown action, said operating means adapted to serve as a check or stop for limiting the breakdown movement of the barrel.

5. In an ejector mechanism of the character described, the barrel-lug having the longitudinal ejector-bore, a vertical slot beneath said bore, and the transverse holes or openings through the sides of said lug, said side openings adapted for confining the swing of the catch-lever to a movement within the limit of the ejector-notches; in combination with the ejector-rod having the notch and shoulder, and the pivoted catch-lever provided with a cross-pin or lateral wing-studs that project through said side openings for engagement with shoulders in the frame for actuating said catch-lever; said pin also serving as a check or stop for limiting the breakdown movement of the frame, substantially as set forth.

Witness my hand this 18th day of December, 1899.
